Primary Examiner — David Muller*Assistant Examiner* — Nathan Johnston(74) *Attorney, Agent, or Firm* — Dobbin IP Law, P.C.;
Geoffrey E. Dobbin(57) **CLAIM**

The ornamental design for a glove dispenser, as shown and described.

DESCRIPTION

FIG. 1 is a perspective view of the glove dispenser, showing my new design.

FIG. 2 is an alternate perspective view thereof.

FIG. 3 is a front elevation thereof.

FIG. 4 is a rear elevation thereof.

FIG. 5 is a side elevation thereof.

FIG. 6 is a top plan view thereof; and,

FIG. 7 is an alternate perspective view thereof, focusing on the bottom side.

The broken lines in the figures illustrate the portions of the design that form no part of the claimed design.

1 Claim, 3 Drawing Sheets(56)
